CARBON PAPER HOLDING MEANS FOR
MANIFOLDING TYPEWRITERSWilliam J. Feitl and Elmer J. O'Brien,
Chicago, Ill.

Application April 4, 1949, Serial No. 85,442

12 Claims. (Cl. 197—126)

1

This invention relates to carbon paper holding means for manifolding typewriters in which a plurality of packs of carbon paper are interposed between continuous accordion folded plies for so-called fan-folds of bill-heads or the like upon which typewriter records with multiple copies are simultaneously to be made, the carbon paper packs being attached to a cradle which moves forward with the work as the typewriter platen is turned and which is retracted with respect to the work when a bill-head form is completed and withdrawn from the typewriter. In this retractive movement of the cradle, the carbon packs slide rearwardly between the bill-head plies until the forward edge of the carbon sheets register with the upper edge of the next bill form to be worked upon, and these operations are repeated until the exposed section of carbon of the packs is worn out, whereupon it is desirable to be able to tear off the worn-out section and pull forward a new section of carbon paper from a pack without removing the pack from the cradle.

While an accordion-folded pack permits a new section of carbon to be pulled out in this way, difficulty has been encountered in providing means for securely holding the accordion folds from accidentally unraveling when the cradle is moved back and forth, and only permitting such unraveling when the operator desires to discard a worn-out section and extend a new length of carbon. In Feitl Patent No. 2,363,661 of November 28, 1944, means are disclosed and claimed for clamping all but an extended operating section of the carbon upon a holding sheet, the clamping means there shown, however, requiring the operator to place her hands well between the fan-folds or plies of the work to release and re-secure the clamping means, that operation being time consuming, particularly since it must be done for each of a plurality of packs which may be as many as a dozen for commercial billing in large business establishments where as many as thirteen copies of a bill form may be frequently typed simultaneously.

Among other objects the present invention aims to provide means for releasing and re-securing an operative carbon paper section, that is accessible at a margin of the manifold pile, and that requires a minimum of manipulation by the operator, the holding means being desirably integral with the carrier for the carbon paper supply and thus avoiding removable elements.

In an important aspect, the present invention further provides holding mechanism, which may be characterized as a buckle device, through which

2

the carbon paper may be threaded when the pack is initially assembled and which has an actuating member for readily locking or releasing the carbon paper, thus providing metering means by which selectively determinable lengths of the carbon paper may be drawn at will, thus effecting enhanced economy of carbon supply.

More generally, the invention provides improved and simplified holding means of the class referred to.

These and other objects and advantages will be apparent from the following description, taken with the accompanying drawings, of an illustrative embodiment of the invention, and in which drawings:

Figure 1 is a perspective somewhat schematic view of a manifold pile having a carbon pack cradle associated therewith, the ends of the manifold pile being discontinued, one of the packs (without the carbon paper however) being also shown with the present invention applied thereto, a retracted position of the cradle and pack being indicated in dotted lines;

Figure 2 is an enlarged cross-section of a manifold pile taken as on the line 2—2 of Fig. 1, but four carbon packs being indicated, one less than the five plies shown in the pile;

Figure 3 is a separated plan view, on the scale of Fig. 2, of carbon holding means following the present invention, an alternative position of the actuating member thereof being indicated in dotted lines;

Figure 4 is a perspective view, parts being broken away for clearness of description and to save space, of a carbon pack, including a buckle device embodying the present invention, in position for drawing out a length of carbon paper;

Figure 5 is a fragmentary perspective view similar to Fig. 4, but showing the buckle device in holding or clamping position;

Figure 6 is a side view of the pack shown in Fig. 4, but with the buckle actuating member in still another position such as may be employed when the carbon is first assembled in the pack and threaded through the buckle, and;

Figure 7 is a plan view on a much smaller scale of a carbon pack as shown in Fig. 4, but indicating a full operative section of carbon paper extended for use.

Referring in detail to the illustrative construction shown in the drawings, the numeral 11 indicates an intermediate portion of a manifold pile of bill-heads or the like, drawn continuously from a large supply (not shown) of perforatedly connected forms and which is to be fed forward

around a typewriter platen, five plies 12, 13, 14, 15 and 16 being here shown for illustration. Between each of the plies is interposed a carbon paper pack such as 17, only one of which is indicated in Fig. 1, to avoid confusion, but the presence of four of which is indicated in Fig. 2, one less than the number of manifold plies. The carbon packs are commonly all attached to a cradle diagrammatically indicated at 18, which by well-known mechanism not here necessary to be described moves laterally with the manifold pile and also forwardly with the pile as the typewriter carriage and platen are manipulated, and which also may be retracted with respect to the pile and carriage, to the position indicated in dotted lines at 18a. The cradle 18 may mount the carbon packs 17 each by a blade 19 which has an elongated aperture 20 therein at its outer end for being impaled on a cradle post 21, a blade with its carbon pack being interleaved between the manifold plies alternatively at opposite sides of the pile, the cradle having a post 21 at each end for this purpose and the blades being thus alternatively right and left.

In accordance with the present invention, the apertures 20 and the posts 21 are correspondingly elongated to maintain the blades 19 normal with respect to the line of movement of the manifold pile toward the platen, indicated by the arrow 22, and the blade has a slot 23 (Fig. 4) therein, through which the cover flap 24 of the carbon pack carrier 25 is threaded, thus placing the body of the blade 19 in the bight 26 of the carrier and retaining the blade well within the bight and also preventing the carrier sheet 25 from being accidentally displaced on the blade.

Further in accordance with the present invention, the forward edge of the carrier sheet 25 is adapted to have secured thereto the carbon paper buckle device following the present invention, indicated generally by the numeral 27, and which is illustrated in separated view in Fig. 3. Buckle device 27 in this instance includes a yoke bar 28 which is secured to the forward edge of the carbon carrier sheet 25 as by being passed through the bight portion 29 of the carrier sheet formed by folding this edge of the carrier sheet upon itself as at 30 and securing these edge parts together, preferably the lateral edges of the carrier as by tape 30a, and thus forming a pocket 30b for the carbon paper between the carrier sheet 25 and its folded over edge portion 30. At one end, the yoke bar 28 has a forwardly extending arm 32 in which is journaled as in a socket or sleeve 32a in the end of the arm, pintle 33 of detent bar 34, which extends alongside the yoke bar 28, and at its other end has a finger-grip or handle 35 projecting beyond the yoke bar 28 for ease of accessibility and manipulation. The pintle 33 is journaled in the arm 32 loosely so that the detent bar may have a swivel or wrist motion as well as a rotary movement with respect to the yoke bar. One alternative open position of the detent bar is indicated at 34a (Fig. 3) and another such alternative position at 34b (Fig. 6), for purposes presently explained. The pintle 33 may be upset or swaged slightly as at 36 to hold the detent bar loosely in the socket 32a of the yoke bar arm 32.

At its other end, adjacent the handle 35, the yoke bar 28 carries a lock member here shown in the form of a clip or hook 37, such as a wire firmly secured to the yoke bar by any suitable means and bent upon itself to provide an open spring

loop into which the detent bar may be pressed to hold the detent bar in either one of its alternative locked positions, one of which is shown in Fig. 4 and the other in Fig. 5, as presently more fully explained.

Still further in accordance with the present invention, the detent bar 34 carries a trammel element or strip 38 which may be provided, as in this instance, by forming a slot 39 in one edge of the detent bar, the trammel strip 38 thus being integral with the detent bar.

In practice the carbon pack includes in addition to the holding means, the usual carbon paper which is desirably in the form of a continuous web 40 of considerable length, preferably accordion-folded as illustrated, and disposed on the carbon carrier sheet 25 between the latter and its flap 24 so that the transfer side or pigmented face 41 of the carbon is uppermost when an operative length or section of carbon, such as 42, is drawn from the pack for use. It will be understood in the art that by disposing the pigmented face uppermost in the pack, it will come nethermost on the typewriter platen between the bill-head plies.

Operation of the present novel expedients is as follows:

A complete carbon pack is shown in Fig. 7, including carbon paper and holding means, there being one of these packs between each two contiguous plies of the manifold pile, the alternate plies and carbon packs being thus superposed one upon another. In assembly the flap 24 is put through the slot 23 of the mounting blade and the various right and left packs arranged alternately on the cradle posts between the respective manifold plies, the latter sliding over the packs during the manifolding operation. It will be understood that the buckle devices 27 are also formed right-hand and left-hand, respectively, corresponding to a blade 19 of each, Figs. 1, 4, 5, 6 and 7 depicting a right-hand pack. Fig. 2 indicates both right-hand and left-hand packs.

When the carbon paper supply web 40 is initially placed in the pack as already referred to, the top fold thereof is drawn out by the operator and passed through the space between the yoke bar 28 and the detent bar 34 of the buckle device 27. To facilitate this operation, and as shown in Fig. 6, the detent bar 34 may be released from the hook 37 and raised to dispose the carbon thereunder. Next, the carbon paper is threaded through the slot 39 in the detent bar bringing the carbon paper over the trammel strip 38. Thereupon, the detent bar may be temporarily secured to the yoke bar by the hook 37, as seen in Fig. 4.

When the pack is assembled and the buckle device is in position, as seen in Fig. 4, for example, the carbon paper may be pulled out or fed by the operator to the extent desired (which is usually about as seen in Fig. 7) the carbon paper at this time sliding through the buckle device. When the desired length of carbon such as 42 has been drawn out for initial operation, the operator may then lock the carbon paper by first releasing the detent bar from the hook 37, and turning the bar over, on its pintle 33, with respect to the yoke bar 28. This action buckles or curls the carbon paper upon itself about the detent in a replicate fold as seen in Fig. 5, the trammel strip 38 now lying next adjacent the yoke bar 28 and having carried the carbon paper over with it. To complete the locking operation, the detent bar is re-secured to the lock member

5

or hook 37 (Fig. 5). Any stresses on the carbon paper tending to draw it from the carbon web 40 are thus prevented from doing so until the operator desires to draw out or feed more carbon. In lieu of temporarily securing the detent bar as in Fig. 4 when feeding carbon, the operator may hold the handle 35 in position with one hand while pulling out the carbon with the other.

Use of the carbon packs with the parts in the position shown in Fig. 5 contemplates forward movement of the carbon, carbon packs and cradle simultaneously with the manifold pile as a bill-head is being typed upon, and then retraction of the cradle, carbon packs and carbon paper simultaneously with respect to the manifold pile for the typing of the next bill-head in the continuous pile.

When now a forward length of the carbon becomes worn by use, which may occur as to one or more of the packs and generally as to all of them at the same time, and the operator desires to provide a new forward length, this may be done by tearing off the used carbon, releasing the detent bar of a carbon pack from the position shown in Fig. 5, turning it over upon itself and re-securing it in the position shown in Fig. 4. This at the same time uncurls the carbon paper and permits the latter to slide or feed through the buckle device 27 when pulled out, to the extent desired, the accordion folds of the carbon paper unfolding for this purpose (Fig. 4). Thereupon the operation is reversed and the detent bar relocked in the position of Fig. 5, which again prevents carbon from being pulled out of the pack.

So constructed and arranged, the finger piece or handle 35, together with the detent bar 34, functions as an actuating member for the carbon supply that is accessible at a margin of the manifold pile, and which minimizes the need for the hands of the operator to be inserted between the plies to draw a new length of carbon from the pack; only enough of the hand of the operator need be inserted to get a grip on the paper and pull it forward, the manifold plies being sufficiently flexible for this purpose.

Furthermore, since the buckle device 27 is an operative part of the carrier sheet 25 and permanently attached thereto, no loose parts are required which could become misplaced or lost. The pack carrier, typified by the parts 25 and 27, may be sold as a unit to be virtually permanently assembled with the manifolding mechanism. This merely necessitates replenishment at relatively long intervals of a fresh carbon paper supply, typified as at 40. The user having once purchased the carrier with its associated buckle device, need then only purchase the accordion folded carbon paper, thus effecting economy in cost of operation of the manifolding unit.

Still further, the buckle device here disclosed provides feeding or metering means whereby any desired length of carbon paper may be drawn from the pack and the carbon locked at any selectively determinable point, thus avoiding the necessity for drawing out only predetermined units or sections of the carbon paper and avoiding any necessity to throw away unused portions. Further ease and economy of operation is thus effected.

It will be seen that the parts including the mounting blade, carrier, yoke bar, socket arm, detent bar, hook, and handle are made desirably flat so as to offer a minimum of thickness of parts between the manifold plies and a minimum of

6

friction to movement of the plies with respect to the carbon packs. Also the flat detent bar with its flat trammel strip facilitates the curling or doubling actions on the carbon paper for holding purposes while avoiding any tendency to tear the paper.

The pocket 30b advantageously holds the body of the carbon supply from shifting out of line during the manipulations of the manifolding mechanism and maintains it in position to feed evenly through the buckle device, the pocket at the same time not preventing the desired unraveling of the carbon paper when fed forward as in Fig. 4, to provide a new usable length. The cover flap 24 further assists in maintaining the carbon supply in position and protects it from tractive influences of the manifold pile.

It will be understood that the term "carbon paper" is intended to include any pigmented or other transfer sheet, the term "typewriter" any similar manifolding mechanism, and the term "bill-head" any typewritten work.

Furthermore, the invention is not intended to be limited to details of construction shown for purposes of illustration of one practical embodiment, and such changes may be made as fall within the scope of the appended claims without departing therefrom.

The invention having been described, what is here claimed is:

1. Holding means of the class described, comprising, in combination, a mounting blade, a carrier sheet mounted on said blade, said carrier sheet being adapted to support a folded supply of carbon paper or the like, and a slotted device permanently carried by the carrier sheet for selectively gripping the carbon paper to limit the extent of withdrawal of the paper from the carrier sheet, said device including a rotatable actuating member extending completely across the carrier sheet and accessible at a lateral margin of the carrier sheet.

2. Holding means of the class described, comprising in combination, a carrier sheet adapted to support a folded supply of carbon paper or the like, a member secured to and extending across the forward margin of said carrier sheet, a socket at one end of said member, an element pivoted in said socket and also extending across the forward margin of said carrier sheet, and locking means for said element on said member at the other end of said member.

3. Holding means of the class described, comprising, in combination, a mounting blade, a carrier mounted on said blade, said carrier being adapted to support an accordion folded supply of carbon paper or the like, and a buckle device carried by the carrier along the forward margin of the carrier for selectively gripping the paper to limit the extent of withdrawal of the paper from the carrier, said buckle device including a slotted element accessible at a lateral margin of the carrier for operation of said element.

4. Holding means of the class described comprising, in combination, a carrier adapted to support an accordion folded supply of carbon paper or the like, and a buckle device for paper on the carrier, said buckle device including a slotted trammel bar extending across the paper and adapted to be rotated to one position to fold the paper upon itself to hold the paper with respect to the bar, and to another position to permit the paper to slide thereover.

5. Holding means of the class described comprising, a carrier sheet for a supply of pigmented

paper or the like folded on the carrier sheet, a buckle device on the carrier sheet having a slot through which a leading end of the paper may be threaded and lockably engaging the paper, and an actuating element for locking or unlocking the buckle device, whereby usable lengths of the paper may be metered at will by the operator.

6. Carbon paper holding means for manifolding typewriters comprising, the combination with a carrier sheet for a supply of accordion-folded carbon paper, of a flat yoke bar permanently secured to the carrier sheet, a forwardly extending arm at one end of said yoke bar, a socket at the outer end of said arm, a pintle loosely journaled in said socket, a flat detent bar integral with the pintle, a slot in said detent bar providing a trammele strip portion of the detent bar, the paper being disposable under the detent bar and through said slot, and a hook at the end of the yoke bar opposite said arm for releasably securing the detent bar thereto in either of two selective positions, in one of which the carbon paper may be slid through the slot, and in the other of which the paper is curled upon itself to grip it against movement therethrough, the detent bar being extended beyond said yoke bar to provide a handle for the detent bar.

7. Carbon paper holding means, comprising, in combination, a mounting blade, a carrier mounted on said blade, said carrier being adapted to support a folded supply of carbon paper, and a device carried by the carrier for selectively gripping the carbon paper to limit the extent of withdrawal of the paper from the carrier, said device including an actuating member accessible at a lateral margin of the carrier, said device having a slot therein passing the paper therethrough, and said device being rotatable with said paper in said slot to fold the paper upon itself.

8. Carbon paper holding means comprising, in combination, a carrier, said carrier being adapted to support a folded supply of carbon paper, and a device carried by the carrier for selectively gripping the carbon paper to limit the extent of withdrawal of the paper from the carrier, said device including an actuating member accessible at a lateral margin of the carrier, the member having a slot therein for passing the carbon therethrough and being rotatable to fold the paper upon itself for gripping action thereon.

9. In carbon paper holding means or the like, in combination, a carrier, said carrier being adapted to support a supply of carbon paper, and a device carried by the carrier for selectively gripping the carbon paper to limit the extent of withdrawal of the paper from the carrier, said device including a rotatable actuating member accessible at a lateral margin of the carrier, the device having a pair of slots for threading the

carbon paper therethrough, whereby the paper may be curled upon itself to secure it.

10. Carbon paper holding means, comprising, in combination, a carrier adapted to support a folded supply of carbon paper, a member secured to and extending across the said carrier, a socket at one end of said member, an element pivoted in said socket and also extending across the said carrier, and locking means for said element on said member at the other end of said member, the locking means being in the form of a hook carried by the member and receiving said element.

11. Carbon paper holding means comprising, in combination, a carrier adapted to support a folded supply of carbon paper, a member secured to and extending across the said carrier, a forwardly extending arm at one end of said member, a socket carried by said arm, an element pivoted in said socket and also extending across the said carrier, and locking means for said element on said member at the other end of said member.

12. Carbon paper holding means for manifolding typewriters, comprising, a carrier sheet for a supply of accordion-folded carbon paper, the carrier sheet having a pocket adjacent its forward edge to receive the carbon paper, a flat yoke bar permanently secured to the carrier sheet adjacent its forward end, a forwardly extending arm at one end of said yoke bar, a socket at the outer end of said arm, a pintle loosely journaled in said socket, a flat detent bar integral with the pintle, a slot in said detent bar, the forward end of the paper being disposable under the detent bar and through said slot, a hook at the end of the yoke bar opposite said arm for releasably securing the detent bar thereto in either of two selective positions, in one of which the carbon paper may be slid through the slot, and in the other of which the paper is curled upon itself about the detent bar to grip it against movement therethrough, the detent bar being extended laterally beyond said yoke bar to provide a handle for the detent bar, and a cover flap on the carrier sheet for overlying the carbon paper supply.
